DESIGN FOR A COMPARATOR BLANK

Ralph R. Bostic, Los Angeles, Calif.

Application July 25, 1942, Serial No. 107,676

Term of patent 14 years

To all whom it may concern:

Be it known that I, Ralph R. Bostic, a citizen of the United States, residing at Los Angeles, in the county of Los Angeles and State of California, have invented a new, original, and ornamental Design for a Comparator Blank, of which the following is a specification, reference being had to the accompanying drawing, forming a part thereof.

In the accompanying drawing, the figure is a plan view of a comparator blank showing my new design.

I claim:

The ornamental design for a comparator blank, as shown.

RALPH R. BOSTIC.
